HANS PETERSEN, OF DAVENPORT, IOWA, ASSIGNOR TO THE LINOGRAPH COMPANY,
OF DAVENPORT, IOWA, A CORPORATION.

LINOTYPE-MACHINE.

1,179,454.

Specification of Letters Patent. Patented Apr. 18, 1916.

Application filed July 13, 1915. Serial No. 39,717.

To all whom it may concern:

Be it known that I, HANS PETERSEN, a citizen of the United States, residing at Davenport, in the county of Scott and State 5 of Iowa, have invented certain new and useful Improvements in Linotype-Machines, of which the following is a specification.

The invention relates to improvements in linotype machines. In machines of this 10 nature arranged for matrices with two or more superposed intaglio characters, the slide, second elevator, or other device which presents the composed line of matrices and space bars to the mold or mold wheel for 15 the casting of the linotype, is provided with horizontal ledges at the upper and lower portions thereof, and the matrices are provided with ears or lugs at the upper and lower ends thereof adapted to coöperate respectively with the said horizontal ledges of 20 the support or slide, the ears or lugs at the upper ends of the matrix being adapted to slide and rest upon the uppermost horizontal ledge to support the matrix at its lowermost 25 level, and the lugs or ears at the lower end of the matrix being adapted to be engaged with and rest upon the lower horizontal ledge to support the matrix in its uppermost 30 adjusted position. This arrangement presents the defect, that the alinement of the letters in the cast line when cast from raised 35 matrices is soon rendered irregular, as the bottom faces of the lower ears or lugs of the matrices become worn away much more rapidly than the other supporting faces of 40 the matrices since each matrix constantly and repeatedly drops and strikes with its lower ears or lugs various machine parts and the other matrices, and when raised it 45 is exclusively guided by its lower ears nearly during its entire passage through the machine. The matrices with two or more superposed intaglio letters are supported on the bottom faces of their upper ears or lugs 50 like ordinary matrices with single intaglio letters only in case their upper or uppermost intaglio letters are used for casting the linotypes. When the lower intaglio letters or characters are to be used for casting the 55 linotypes, of course, the respective matrices require to be raised into their upper or any

of the upper positions, so that the bottom faces of their upper ears remain at a height above the guiding shoulders of the slide, second elevator, or other device, and consequently the respective ledge or ledges in the device will have to engage beneath the lower rear ears of the matrices for supporting and guiding the latter. It is thus obvious, that after the bottom faces of the lower ears have 60 been more or less worn away the several letters of characters in the linotype cast from raised matrices will no longer be alined, they being more or less lowered in proportion to the wear of the bottom faces of the lower 65 rear lugs of the respective matrices. As the intaglio letters in the matrices representing different fonts are used differently one font being employed much more than the other or any of the others, it follows, that the respective matrices are not used uniformly and consequently their lower rear lugs will be irregularly worn away. For this reason also the alinement of the letters in the cast 70 linotype cannot be maintained any longer. 75 It has heretofore been proposed to remedy this defect by providing the slide or support for the composed matrices, with a flange extending inwardly beyond the plane of the edges of the matrices and adapted to support the matrices by contact with the portion of the lower ends thereof within said plane. But such a construction necessitates the cutting away of the space bars so that the matrices and space bars are of unequal 80 width and also requires the formation of additional recesses in the matrices. 85

The object of the present invention is to provide an improved construction whereby this difficulty will be entirely avoided, and one which will be very simple and inexpensive and that will not require the cutting down or the use of space bars of less width than the width of the matrices. 90

The invention will be understood from the following detail description when considered in connection with the accompanying drawings wherein I have illustrated a preferred embodiment thereof. 95

In the drawings: Figure 1 is a vertical 100 cross section through a part of a mold wheel, the mold, and the slide or first ele-

vator or other device in a plane adjacent a matrix occupying its lower position, while another matrix behind the same occupied its upper position, all of the matrices being assembled to be provided with only two superposed intaglio letters or characters. Fig. 2 is a similar section in another plane adjacent a matrix occupying its upper position, while another matrix behind the same occupies its lower position. Fig. 3 is a side elevation of one of the matrices. Fig. 4 shows one of the space bars, and Fig. 5 is a section taken on the line 5—5 of Fig. 3.

In the drawing, 2 denotes the mold, and 3 the slide, first elevator, or other device for presenting the line of composed matrices to the mold.

In accordance with the present invention, the spaced opposing walls of the slide or device 3 are provided with superposed grooves 4. The matrices are provided at their upper ends with oppositely disposed ears or lugs 5, the height of which is less than the difference in level of the plural characters 6 of the matrices, said ears or lugs 5 being adapted to be engaged with the upper grooves 4 with their under faces 5' resting upon the lower walls 4' thereof to support the matrices in position to cast type from the lower character thereon and to be engaged with the lower set of grooves 4 with their lower faces 5' resting upon the lower walls 4' thereof to support the matrix in position to cast from the upper character thereon.

It will be remarked that the support for the matrices at the different levels to which they are adapted to be adjusted is provided through the single pair of ears 5 at the upper end of the matrix entirely removed from and independent of the bottom face of the matrix, and which practically undergo no wear or tear so that the alinement of the characters is assured. It will also be observed that the supporting ledges of the slide or support for the composed line of matrices are within the vertical plane of the opposing walls of the slide, and that this construction does not necessitate the recessing of the matrices, or the special formation or cutting away of the space bars the use of space bars and matrices of equal width being permitted.

8 designates one of the space bars provided with oppositely disposed supporting ears 8', said ears being shown somewhat longer than the supporting ears or lugs of the matrices and being adapted to engage one of the grooves 4, which for this purpose is somewhat extended as shown to accommodate the longer supporting lug.

In the particular construction illustrated in the drawings, the matrices are shown provided with two superposed characters and the support or slide with two sets of grooves 4. When the matrices are provided with a

greater number of superposed characters the sets of grooves are correspondingly increased.

I desire it to be understood that modifications and changes in the particular construction illustrated in the drawings as will appeal to those skilled in the art and falling within the scope of the appended claims may be made without departing from the spirit of the invention.

What I claim is:

1. In a linotype machine, the combination with a matrix provided with a plurality of characters at different heights and having a pair of oppositely disposed ears of equal height at its upper end, of a device for presenting matrices to the mold, said device having spaced opposing walls each provided with a plurality of superimposed grooves extending longitudinally thereof, the grooves of the opposing walls being arranged to provide sets of parallel grooves at different heights adapted to receive the ears at the upper end of the matrix, the under faces of said ears being adapted to rest upon the lower walls of the grooves and the lower walls of the grooves constituting supporting ledges to sustain the matrix at the different heights to which it is adapted to be adjusted.

2. In a linotype machine, a matrix provided with a plurality of character indentations in one edge and having a pair of oppositely disposed ears of equal height at its upper end, in combination with a mold, and a device for presenting matrices to the mold, said device having spaced opposing walls each provided with a plurality of superimposed grooves extending longitudinally thereof, the grooves of the opposing walls being arranged to provide parallel sets of grooves at different heights adapted to receive the ears at the upper end of the matrix, the under faces of the ears being adapted to rest upon the lower walls of the grooves, and the lower walls of the grooves constituting supporting ledges to sustain the matrices at the different heights to which it is adapted to be adjusted, and space bars of a width equal the width of the matrices.

3. In a linotype machine, a matrix having a plurality of character indentations in one edge and provided with a pair of oppositely disposed ears at its upper end, said ears projecting laterally from the sides of the main body portion of the matrix, in combination with a mold, and a device for presenting matrices to the mold, said device having spaced opposing walls each provided with a plurality of superimposed grooves extending longitudinally thereof, the grooves of the opposing walls being arranged to provide sets of parallel grooves at different heights and adapted to receive the ears at the upper end of the matrix,

the under faces of the ears being adapted to rest upon the lower walls of the grooves, and the lower walls of the grooves constituting supporting ledges to sustain the matrix at the different lengths at which it is adapted to be adjusted, the supporting ears at the upper end of the matrix being of equal width and height, and of less height

than the distance between the matrix characters.

In testimony whereof I affix my signature in presence of two witnesses.

HANS PETERSEN.
